[57] **CLAIM**

The ornamental design for a measuring line spool housing for use in golf, as shown and described.

DESCRIPTION

FIG. 1 is a perspective view of a measuring line spool housing for use in golf showing my new design;

FIG. 2 is a left side elevational view;

FIG. 3 is a right side elevational view; and,

FIG. 4 is a top plan view thereof, the bottom plan view being identical.

FIG. 1

FIG. 2

FIG. 3

FIG. 4
